UNITED STATES PATENT OFFICE.

EDGAR M. BOUTON, OF EAST PITTSBURGH, AND FRANK E. LEWIS, OF EDGEWOOD, PENNSYLVANIA, ASSIGNORS TO WESTINGHOUSE ELECTRIC AND MANUFACTURING COMPANY, A CORPORATION OF PENNSYLVANIA.

ELEVATOR CONTROL.

Application filed December 31, 1921. Serial No. 526,337.

To all whom it may concern:

Be it known that we, EDGAR M. BOUTON, a citizen of the United States, and a resident of East Pittsburgh, in the county of Allegheny and State of Pennsylvania, and FRANK E. LEWIS, a citizen of the United States, and a resident of Edgewood, in the county of Allegheny and State of Pennsylvania, have invented a new and useful Improvement in Elevator Controls, of which the following is a specification.

Our invention relates to motor-control systems and it has particular relation to such systems of control as are employed in connection with elevators, hoists and similar machines.

An object of our invention is to provide an automatic system of speed control which shall be simple in construction, and that shall ensure smooth and economical operation of the driven apparatus.

Another object of our invention is to provide means for guarding against overtravel, which might cause damage to the apparatus or injury to elevator passengers.

Other objects of our invention will be apparent from the following description and the appended claims.

Broadly, the control of a shunt motor by means of armature series and shunt resistance is old, as well as control by means of shunt field resistance. However, many of the systems employed are very complicated and require delicate adjustment and are easily deranged. Apparatus utilizing air or oil dash pots are satisfactory while proper adjustment is maintained. Automatic current limit and counter-electromotive force systems of speed-control and dynamic braking have been used with considerable success but still leave room for improvement.

We propose to employ a current-limit, counter-electromotive force or any other desired system for gradually shunting the starting or armature series resistor, and, in addition to this system, we propose to control the effective value of the armature shunt resistor and the effective value of the shunt-field resistor by switches having a predetermined time element controlled by magnetic means.

Figure 1 is a diagrammatic view of circuits and apparatus embodying our invention;

Fig. 2 is a cross-sectional view of an electromagnet provided with a damper winding;

Figs. 3, 4, 5 and 6 represent, diagrammatically, the successive steps employed in the acceleration of the motor.

Referring particularly to Fig. 1, a shunt motor, having an armature 1 and a shunt field-magnet winding 2, is connected to a source of energy through conductors 3 and 4. The motor may be operatively connected, for example, to an elevator car and maintained at rest in its inoperative position by means of an electromagnetic brake 5. A switch 6 is actuated mechanically by the electromagnetic brake for controlling a circuit comprising resistor 7 to regulate the braking action, as will be hereinafter described.

The direction of rotation of the motor is controlled by reversing switches 8, 9, 10 and 11. Dynamic-braking switches 12 and 13 are mechanically connected to the reversing switches so that switches 8, 10 and 13 are operated simultaneously for one direction of rotation and switches 9, 11 and 12 are operated simultaneously for the reverse direction of rotation. A double-throw line switch 14 is provided with a back-contact switch 15 which provides a shunt circuit for the coil of the electromagnetic brake 5. Limit switches 16 and 17 are provided, one for each direction of travel, and complete the circuit in shunt to the coil of the electromagnetic brake.

A starting resistor 18 and an inductance coil 19, which are connected in series with the motor armature 1, are controlled by electromagnetic switches 21 and 22. A sectional resistor 23, which is in parallel relation with the motor armature and the inductance coil, is controlled by electromagnetic switches 24 and 25 that are normally closed by means of springs 26 and 27. Electromagnetic switch 25 is provided with a damper winding, such as that shown and described in connection with Fig. 2. A dynamic-braking resistor 28 is connected in

parallel to the armature 1 and the inductance coil 19, by switches 12 and 13, and is also in parallel relation to the resistor 23. An electromagnetic switch 29 controls a portion of resistor 23 and is controlled by the reversing switches so as to close its contacts after switches 12 and 13 are closed, thereby providing increased dynamic braking effect. A damper-winding is also provided for this 10 switch.

A sectional resistor 30 is connected in series with the shunt field-magnet winding 2. Field relays 31, 32 and 33 are arranged to control the effective value of the field resistor 30. Relays 31 and 33 are provided with damper windings similar to that of switch 25, as shown in Fig. 2. Relay 31 is controlled, in a well known manner, by the last or high-speed point of a master switch 20 (not shown). Relay 32 is initially controlled, in starting, by current from the source of supply and, during dynamic braking, is maintained in its operative position by the counter-electromotive force of the 25 motor armature 1. Relay 33 is controlled in accordance with the position of relay 32 and is also provided with a magnet having a copper damper winding.

It will be apparent that shunt field control 30 is accomplished in two steps, as has been found necessary in the operation of the average motor.

Referring to Fig. 2 of the drawing, a coil of magnet wire is wound on a copper 35 tube or damper winding 34 and the whole is mounted on an iron core 35. When the coil is energized, a moving contact member or switch is attracted into engagement with a core 35, as is well understood by any one 40 familiar with electromagnetic switches.

Upon closure of reversing switches 8 and 10 and line switch 14, a circuit is established for the motor armature 1 extending from line conductor 3 through line switch 14, switch 8, armature 1, inductance coil 19, resistor 18 and switch 10 to line conductor 4. A shunt circuit is also established from line 45 switch 8 through switch 24, a section of resistor 23 and switch 25 to resistor 18.

50 A section of resistor 23 is, therefore, in shunt relation to the motor armature 1 and the inductance coil 19. Operating coil of relay 32 is connected through the contact members of relay 31 to the source of energy between 55 reversing switches 8 and 10. Relay 32 immediately effects the closure of relay 33, the coil of which is thereby connected to the source of energy between line switch 14 and line conductor 4. The closure of relay 33 60 establishes a circuit for the shunt field-magnet winding extending from line conductor 3 through line switch 14, relays 33 and 32 and a shunt field-magnet winding 2 to line conductor 4. The motor is now in condition 65 to start with maximum field excitation.

The operating coil of the electromagnetic brake 5 is energized from a circuit extending from line conductor 3 through line switch 14, reversing switch 8, switch 12, a portion of dynamic-braking resistor 28, conductor 36 and operating coil of electromagnetic brake 5 to line conductor 4. The operating coil of switch 29 is connected in parallel relation to the brake coil so that switch 29 is opened immediately upon the closure 75 of reversing switch 8 and line switch 14.

The release of the brake permits the motor to start and accelerate to its lowest operating speed, corresponding to the first point of the conventional master switch (not 80 shown). The second operating speed is attained by opening switch 25 to insert additional armature shunt resistance. The next higher operating speed is attained by opening switch 24 which interrupts the circuit through the armature shunt resistor 23. Switches 21 and 22 are next closed in sequence, independently, to remove accelerating resistor 18 and inductance coil 19 from the armature circuit. The armature now 90 accelerates to a speed corresponding to maximum field excitation of the motor.

The next and highest operating speed is attained by opening relay 31, which, in turn, effects the opening of relay 32, and inserts 95 a portion of the shunt field resistor 30 in series with the field winding 2. The opening of relay 32 also effects the opening of relay 33, but the operation of relay 33 is delayed on account of its inherent time element, which is induced by the short-circuited damper winding 34 (see Fig. 2). It is well understood that the counter-electromotive force of self induction is maintained for a considerable period of time by the use of a 100 winding of the character described. Therefore, after a period of time determined by the peculiar construction of relay 33, the relay armature is released and the entire resistor 30 is inserted in series with the field 105 winding 2, whereby the maximum motor speed is attained.

Figs. 3, 4, 5 and 6 represent, respectively, the circuits of the foregoing system of control as arranged when the controller is at 115 its first, second, third and fourth operating speed points, respectively.

In slowing down and stopping the motor, the motor connections are established substantially in the reverse order with respect 120 to the connections during acceleration by the successive closure of relays 31, 32 and 33. Next, resistor 18 and inductance coil 19 are connected in series with the armature 1, and the entire resistor 23 is reconnected 125 in shunt relation to the motor armature 1 and the inductance coil 19. When the coil of switch 25 is deenergized, the switch closes after a period which is predetermined by the inherent time-element of the switch mag- 130

net. This period of time is sufficient to prevent reducing the effective value of the resistor 23 until the speed of the motor armature has been reduced to a proper value.

5 Speed reduction is accomplished smoothly at a maximum rate consistent with good commutation of the armature.

In the "off" position, dynamic braking is established by the opening of contactors

10 8 and 10, which causes the armature current to flow in a local circuit comprising a portion of resistor 23 and the inductance coil 19. With switches 8 and 10 in their fully open position, switch 13 is closed and

15 a parallel dynamic-braking circuit is established comprising the armature 1, resistors 28 and 18 and the inductance coil 19. The opening of switch 8 de-energizes the operating coil of switch 29 which closes to reduce

20 the effective value of resistor 23. The closure of switch 29 is delayed by its damper-winding, whereby a graduated dynamic-braking action is insured. Line switch 14 is opened simultaneously with the opening of

25 switches 8 and 10 and back-contact switch 15 establishes a local circuit comprising the coil of electromagnetic brake 5, resistor 7, limit switches 17 and 16 and back-contact switch 15. The opening of switch 14 dis-

30 connects the brake coil from line conductor 3, and the local circuit for the brake coil prevents too abrupt setting of the brake.

The operating coil of back-contact switch 15 is connected in shunt with the coil of

35 the brake 5, when switch 15 is closed, and operating coil of switch 15 is energized by the counter-electromotive force of the brake coil. A firm contact is thus insured between the contact members of switch 15. Switch

40 6, which is actuated by the brake, is adapted to close and short-circuit resistor 7 before the brake is fully set.

It is evident that, by selecting resistor 7 of proper value, the time of setting of the

45 brake is predetermined to apply full pressure of the brake after the motor speed has been substantially reduced by dynamic braking. In case of over-travel, resulting from any unforeseen cause, limit switch 16 or

50 limit switch 17 is opened, depending on the direction of rotation of the motor thus interrupting the local brake circuit and insuring application of maximum brake-shoe pressure in a minimum period of time.

55 Dynamic braking and mechanical braking are, in such an emergency, accomplished substantially simultaneously and the motor is stopped in the shortest possible time.

60 It should be noted that, when the master switch is returned quickly to its "off" position, dynamic-braking connections are immediately established, but, in addition to the gradual insertion of armature shunt resistance, dynamic braking is commenced

with a weak field, and the field is, thereafter, 65 gradually strengthened to its maximum value. To insure a sufficient time interval in which to build up the field, in addition to the time constant of the field itself, relay 31 is of a construction similar to that of 70 switch 25 and is provided with a damper winding.

The reversing switches 9 and 11 operate to reverse the connections of the motor armature 1, and switch 12 is opened to interrupt the dynamic-braking circuit through resistor 28. The coil of electromagnetic brake 5 is energized through switch 13 instead of through switch 12, while the several switches for controlling the motor speed 80 function as previously described for the opposite direction of rotation.

We have described a system, in which the particular advantages lie in the provisions for graduated dynamic braking, wherein 85 we have eliminated apparatus requiring considerable attention for maintenance, and which should, therefore, have wide application in motor control, particularly in passenger-elevator service. Continuity of 90 service, with a minimum of personal attention from the engineer in charge, is recognized as of utmost importance in the design of elevator control systems. We have found by experience that a constant period of time 95 for graduated dynamic braking is the most satisfactory scheme for average load conditions. Also, the use of inductance in the armature circuit aids in graduating the dynamic-braking effect in proportion to variation in load, so that the motor is brought to rest as quickly as is consistent with safe and economical operation.

We claim as our invention:

1. The combination with a shunt motor 105 and controlling means therefor, of an electro-magnetic brake having a shunt operating coil, a source of energy and a coil energized by the counter electromotive force of the brake coil for rendering said controlling means ineffective.

2. The combination with a shunt motor and a line switch, of an electro-magnetic brake, a source of energy and a coil energized by the counter electromotive force of 115 the brake coil for rendering the line switch ineffective.

3. The combination with a motor having a shunt field-magnet winding, and a resistor for connection in circuit with the winding, of a relay controlled by the counter electromotive force of the motor for controlling the resistor to effect an increase in the motor speed, and an electromagnetic damper winding for controlling the relay.

4. The combination with a motor having a shunt field-magnet winding and a resistor for connection in circuit with the winding,

of a relay controlled by the counter electro-motive force of the motor for controlling the resistor to control the motor speed and an electro-magnetic damper winding for controlling the relay.

5. The combination with a shunt motor and two resistors for respective connection in series with, and in shunt relation to, the motor armature, of an electromagnetic switch for controlling one of said resistors to vary the motor speed, and means for magnetically retarding the operation of the switch for a predetermined length of time after the operating coil of the switch has become de-energized.
10. The combination with a shunt motor and two resistors for respective connection in series with, and in shunt relation to, the motor armature, of an electromagnetic switch which normally shunts a portion of the shunt resistor and which, when operated, renders the shunted portion of said resistor effective, and means for magnetically retarding the operation of the switch for a predetermined length of time after the operating coil has become de-energized.

20. The combination with a shunt motor and two resistors for respective connection in series with, and in shunt relation to, the motor armature, of a spring-closed switch which normally shunts a portion of the shunt resistor, an operating coil for opening the switch, and a short-circuiting damper-coil for magnetically delaying the closure of said switch for a predetermined length of time after the operating coil has become de-energized.
30. The combination with a shunt motor and two resistors for respective connection in series with, and in shunt relation to, the motor armature, of a spring-closed switch which normally shunts a portion of the shunt resistor, an operating coil for opening the switch, and a short-circuiting damper-coil for magnetically delaying the closure of said switch for a predetermined length of time after the operating coil has become de-energized.

40. The combination with an electric motor and controlling means therefor, of an electromagnetic brake, a source of energy, a shunt circuit for the operating coil of the brake, for maintaining the counter-electro-motive force of self-induction of said coil for a predetermined length of time after the

source of supply is interrupted, and a switch 45 for opening said short circuit.

9. The combination with an electric motor and controlling means therefor, of an electromagnetic brake, a source of energy, means for connecting the brake coil to the 50 source of energy, a resistor for connection in shunt to said coil, and a switch actuated by said brake for controlling the resistor.

10. The combination with an electric motor and controlling means therefor, of an 55 electromagnetic brake, a source of energy, a resistor for connection in shunt to the brake operating coil, means for connecting said coil to said source of energy and for disconnecting the shunt resistor, and a switch 60 actuated by said brake for shunting said resistor after said source of energy is interrupted and after said resistor is reconnected in circuit.

11. The combination with an electric 65 motor and controlling means therefor, of an electromagnetic brake, a source of energy, a resistor for connection in shunt relation to the brake-operating coil, means for connecting said coil to said source of energy 70 and for disconnecting the shunt resistor, a switch actuated by said brake for shunting said resistor after said source of supply is interrupted and after said resistor is reconnected in circuit, and a limit switch for controlling said shunt circuits.

12. The combination with a motor having a shunt field-magnet winding and a source of energy, of dynamic-braking means for the motor, and additional dynamic-braking 80 means effective a predetermined time after the motor is disconnected from the source of energy.

In testimony whereof, we have hereunto subscribed our names this 23rd day of December, 1921.

EDGAR M. BOUTON.
FRANK E. LEWIS.
